CLAIM

The ornamental design for a power supply apparatus for manicurist tool, as shown and described.

DESCRIPTION

FIG. 1 is a perspective view of the power supply apparatus for manicurist tool of the instant invention.

FIG. 2 is a top plan view of the power supply apparatus for manicurist tool of the instant invention.

FIG. 3 is a bottom plan view of the power supply apparatus for manicurist tool of the instant invention.

FIG. 4 is an elevation view of one end of the power supply apparatus for manicurist tool of the instant invention taken from the left of the power supply apparatus for manicurist tool shown in FIG. 1.

FIG. 5 is an elevation view of the opposite end of the power supply apparatus for manicurist tool of the instant invention taken from the right of the power supply apparatus for manicurist tool shown in FIG. 1.

FIG. 6 is a side elevation view of the power supply apparatus for manicurist tool of the instant invention taken from the left side of the power supply apparatus for manicurist tool shown in FIG. 2; and,

FIG. 7 is the opposite side elevation view of the power supply apparatus for manicurist tool of the instant invention taken from the right side of the power supply apparatus for manicurist tool shown in FIG. 2.
